UNITED STATES PATENT OFFICE.

DAVID L. BARNES, OF CHICAGO, ILLINOIS, ASSIGNOR TO FRANK H. CLARK,
OF SAME PLACE.

CAR-COUPING.

SPECIFICATION forming part of Letters Patent No. 448,003, dated March 10, 1891.

Application filed November 10, 1890. Serial No. 370,985. (No model.)

To all whom it may concern:

Be it known that I, DAVID LEONARD BARNES, mechanical engineer, a citizen of the United States, residing at Chicago, in the county of Cook and State of Illinois, have invented certain new and useful Improvements in Car-Couplers, of which the following is a specification.

My invention relates to car-couplers, particularly that class of such devices known as "vertical plane" couplers, constructed according to master car-builders' standard lines, and has for its object to provide a car-coupler of much lighter and at the same time stronger construction than any similar one with which I am acquainted, to which end the frame thereof is constructed of a top and a bottom piece of pressed sheet-steel, which are spaced apart by filler-blocks and secured together by rivets. The benefits accruing from this arrangement, besides those of lightness and strength, are the insertion of the "knuckle" at its trunnions without cutting away any portion of the bearings, which has heretofore been an element of weakness in this style of coupler, the insertion of the tail-bolt of the draw-bar (after the coupler is put together) with great convenience, and the fact that the parts may be made in dies, securing at once interchangeability and cheapness.

A further object in view in the construction which I adopt is to so arrange the parts that the coupler will work equally well on curves and on tangents, it having been an objection to most forms of automatic couplers that they could not be operated without placing the cars in approximate alignment. By the use of the peculiar knuckle and locking-pin which I have devised, however, the coupler is locked when half closed, as when on a curve; but this locking only prevents its being opened and offers no obstruction to its full closure. When this takes place, as by the oscillation of the train while running or by the application of the brakes or backing of the engine in shifting, it is at once locked fast. This result I accomplish by making the locking-pin with two wings, one engaging the knuckle and the other (which is formed with a series of steps) dropping behind a projection, which secures it against forward motion, from which

engagement it may be released by lifting it by means of the usual chain. These constructions, together with other incidental improvements, are more fully set out in the annexed description and the drawings therein referred to and hereby made a part of this specification, which show the form in which I prefer to embody my invention, while the elements of novelty are particularly designated in the claims.

In the drawings, Figure 1 is a plan; Fig. 2, a vertical section on the line *k* *k* of Fig. 1; Fig. 3, a vertical section on the line *f* *f* of Fig. 1; Fig. 4, a vertical section on the line *c* *c* of Fig. 1; Fig. 5, a vertical section on the line *a* *a* of Fig. 1; Fig. 6, a vertical section on the line *b* *b* of Fig. 1. Fig. 7 is a plan, Fig. 8 a front elevation, and Fig. 9 an end elevation, of the knuckle; and Figs. 10 and 11 are respectively a front elevation and a plan of my improved locking-pin.

Referring by letter to the accompanying drawings, A represents the top part of my improved draw-head, which is made of pressed sheet metal, as formerly described, in two parts A and B. (Shown best in Fig. 2.) These two parts are kept apart by their sides being turned over until they touch at C C', and are further re-enforced at the part C by the filler-block D, through which, and also through the lip H of the draw-bar stop I, as well as the two parts of the draw-head, pass the rivets E E', securing all the parts firmly together.

At the rear end of the draw-bar a different construction is preferably used. Instead of a solid filler, as at D, a thick wrought U-strap G, of iron or steel, is employed, the rivets F F' securing the strap to the draw-head parts. Through the center of the strap is a hole registering with a space left in the ends of the two parts of the draw-head, through which passes the tail-bolt T of the draw-bar, which may be of any pattern, and (forming no part of my invention) is not shown. By this construction I am enabled to leave an opening K at the side of the draw-head, through which to insert the tail-bolt T. Under ordinary circumstances (as when made of malleable castings or similar stuff) it would be inexpedient to cut away so much of the head as is necessary to attain the object mentioned; but by

using the material which I prefer there is an abundantly large factor of safety after this to allow of the construction adopted. It is manifest that the cutting out may be done on one or both sides of the draw-head, and in some cases even on the top and bottom, the amount varying according to the load to be carried, at the discretion of the designer.

The shape of and the arrangement of parts in the coupler-head, which incloses the knuckle and locking-pin, may be understood fully from various sections shown on Sheet 3 of the drawings, taken in connection with Figs. 1 and 2. It is approximately a box open on the front only. The sides are formed by a deep flange projecting from the parts A and B of the head. It is manifest, however, that metal might be saved and weight reduced by reducing the depth of these flanges, as shown by the dotted lines N N' of Fig. 5. Where this is not done, or wherever the sides are brought together, as in Fig. 4, I provide a tenon or dowel, (shown at M,) which may be of any suitable shape. The object of this is to prevent the displacement of the sides of the box by buffing strains or oscillation of the train. As many of these tenons may be employed as the designer shall think fit. Another spacer or filler is inserted and secured by a rivet at D, Fig. 1. The draw-bar stop I, Figs. 1, 2, and 3, is also made of pressed sheet-steel, preferably in the form shown; but any other substantially similar form may be adopted, the essential features being that it shall have an approximately vertical face R, either corrugated or flat, and an inclined corrugated face Q, serving as a brace or stay. The stop is secured to the top A of the draw-bar by the rivets E E', as described, and also by the rivets P P', passing through the lip H', as shown in Figs. 1 and 2. The great advantage of the stop, as thus constructed, is the facility with which it may be replaced if accidentally destroyed or found to contain a flaw. Heretofore when this has been the case the whole coupler had to be thrown away. Although the strength of my device will lessen the chance of this happening, it may still occur at times. It is manifest that the rivets P P' may be replaced by bolts, though this is not a desirable construction.

It is also evident that my improved draw-bar stop might be easily applied to old couplers by any one skilled in the art after cutting away the broken part.

In the two parts of the coupler-heads are formed bearings S S' for the knuckle-trunnions. These are shown fully in Figs. 1, 2, and 4, and form the main bearing of the knuckle. As an additional security against the giving way of the knuckle-trunnion, a pin T, Fig. 2, with an upset head, is passed through the hole in the bearings and through the trunnions. The other end is then upset or riveted by a hammer, unless it is thought best to use a bolt and lock-nut.

The knuckle L used in this coupler is of peculiar form and is fully illustrated in Figs. 7, 8, and 9. It is also shown in dotted lines in its place in Fig. 1 and partly in full and partly in dotted lines in Fig. 2, and consists of a main body and a wing with flanges.

S² S³ represent the trunnions around which the knuckle revolves.

U' U² are the flanges which strengthen the wing U, engaging the locking-pin.

X is a portion cut away to save weight, and in the same manner the depressions X' X' (see Fig. 9) are introduced to save metal. Cores X² X³ extend from the hole through which passes the pin T for the same purpose. These cores of course remove only the metal along and near the neutral axis, or that portion of the knuckle which is not strained in buffing or pulling the train.

In Fig. 8 it will be observed that the metal of the top and bottom parts A and B of the draw-head (shown in dotted section) is depressed to fit snugly against the trunnions S² S³ and the depressed part of the knuckle, serving to re-enforce these parts against the shocks incidental to making up and stopping trains. These being parts which are often broken, thus strengthening them prolongs the life of the coupler. It is of course necessary that this depression should not bind the parts, but form only a working fit.

In couplers for use on heavy cars it is desirable to extend the bearing-surfaces of the knuckle, and this may be done by forming the bosses or projections Y Y' so as to preserve the full bearing depth.

The locking-pin is shown in Figs. 10 and 11 and is shown in operative position in Figs. 1 and 2. It consists of a central shank or pin 2, provided with two flanges c and f. The flange or wing c has two or more steps d and e formed on its under side, the use of which will be hereinafter pointed out. The pin is further provided with a ring a for the insertion of a chain, and a bearing b, below which projects a journaling portion h. The flange U² of the knuckle engages the pin between the face g of the wing c and the wing f, as best shown by dotted line in Fig. 1, where the coupler is shown locked. Its operation is as follows: When it is desired to release the coupler, the locking-pin Z is lifted up by the chain until the lowest step d on the wing c is raised above the stop i, formed on the lower part B of the draw-head, as seen in Fig. 2. The knuckle then rotates outward on its bearings. The flange U² engages the face g of the wing c and rotates the locking-pin over the flange or stop i, so that the pin can no longer drop behind it, and thus return to a locked position. At the same time the wing f is engaged by the rim U of the knuckle and prevents the pin from rotating past the center. Lest the knuckle should open so far that the wing f would pass behind its corner and bind, a stop k is made on the knuckle or draw-head either in the form shown or in any other suit-

able manner. The operation of this coupler on a curve may be thus described. When the buffers come together, if the curve be a sharp one, the wing *f* of the locking-pin will be engaged and pushed back by the wing *U* of the knuckle, which is a cam eccentric toward the point *l*. The pin being thus rotated, the wing *c* is drawn in until the step *d* thereon drops behind the flange *i* in Fig. 2. The coupler is thus locked, though only partly closed. If the curve be of greater radius, the pin would rotate until the step *e* engaged, in either event closing completely when the cars come together on a straight line. While on such a line, should the coupling occur there, the full closure would occur at once, the knuckle being prevented from closing too far by the flange *U'* striking the side of the head.

As in all couplers of this class, the usual slot *W* and pin-hole *T'* are provided for use with an ordinary link.

It is manifest that the upper and lower parts *A* and *B* of my coupler might be made at the same time in a die of sufficient size to embrace them both and one part be then bent over the other; but I consider this a mere modification of my invention and fully within its scope.

Other changes suggest themselves, as that the parts of the draw-head may be welded together, a block or spacer substituted for the **U**-strap at the rear, &c., and all such changes I aim to embrace herein.

Having thus described my invention, what I claim, and wish to protect by Letters Patent of the United States, is—

1. In a car-coupler, a draw-head made of sheet metal in two parts and having flanges, as described, kept in relative position by suitable tenons, substantially as described.

2. In a car-coupler, a draw-head made, as described, in two parts, secured together at the rear ends by a **U**-strap, block, or spacer, and riveted, substantially as described.

3. In a car-coupler, a draw-head made, as described, in two parts, secured together at their rear ends by a **U**-strap and rivets, the strap having a hole registering with a cut-away portion of the two parts and adapted to receive the tail-bolt, substantially as described.

4. In a car-coupler, a pressed-metal draw-head made in two parts secured together, whereof the lower part is provided with a lug or flange adapted to engage the locking-pin, substantially as described.

5. In a car-coupler, a pressed-metal draw-head wherein the metal of the head is depressed to form a working fit around a portion of the rear side of the knuckle, thus reinforcing it against shocks, substantially as described.

6. In a car-coupler, a detachable pressed-metal draw-bar stop adapted to be secured to the draw-bar, substantially as described.

7. In a car-coupler, a detachable pressed-metal draw-bar stop having a vertical stop-

face and an inclined face serving as a brace, substantially as described.

8. In a car-coupler, a detachable pressed-metal draw-bar stop having a vertical stop-face and an inclined face serving as a brace, one or both of the faces being corrugated to obtain greater stiffness, substantially as described.

9. In a car-coupler, a detachable pressed-metal draw-bar stop having a vertical stop-face, an inclined face serving as a brace, and lips or flanges *H H'*, whereby the stop may be secured to the draw-bar, substantially as described.

10. In a car-coupler, a detachable pressed-metal draw-bar stop having a vertical corrugated stop-face, an inclined corrugated face acting as a brace, and lips or flanges adapted to secure the top to the draw-bar, substantially as described.

11. In a car-coupler, a rotating knuckle having a wing *U*, provided with the flange *U' U'*, and a cut-away portion *X*, substantially as described.

12. In a car-coupler, a rotating knuckle having trunnions formed integrally therewith, and a wing *U*, provided with flanges *U'* and *U''* and adapted to engage a suitable locking-pin by the shock of coupling, substantially as described.

13. In a car-coupler, a rotating knuckle having a wing or flange preventing the locking-pin from turning to a locked position while the knuckle stands open, substantially as described.

14. In a car-coupler, a locking-pin consisting of a shank or round body *Z*, a wing *f*, adapted to engage the knuckle, and a wing *c*, adapted to engage a projection on the draw-head, substantially as described.

15. In a vertical-plane car-coupler, a locking-pin consisting of a shank or round body *Z*, a wing *f*, adapted to engage the knuckle, and a wing *c*, provided with one or more steps *d e*, adapted to engage a projection on the draw-head at different points in the rotation of the pin, substantially as described.

16. In a vertical-plane car-coupler, a locking-pin made as described and adapted to be rotated outward by the knuckle when lifted up to free the wing *c* from a projection on the draw-head, substantially as described.

17. In a vertical-plane car-coupler, a locking-pin made as described and adapted to be rotated by the closing of the knuckle to such a point as will permit the wing *c* to drop behind a locking projection on the draw-head, substantially as described.

18. In a car-coupler, the combination of a draw-head made in two parts, as described, each part formed with a trunnion-bearing of unbroken circumference, and a knuckle having integrally-formed trunnions adapted to turn in such bearings, with a pin or bolt passed through the axis of the trunnions securing the parts together, substantially as described.

19. In a car-coupler, the combination of a pressed-metal draw-head made in two parts, as described, spaced apart by filler-blocks and secured together by rivets having its rear end 5 re-enforced with a **U**-strap, and a trunnion-bearing of unbroken circumference formed in each part, with a knuckle adapted to rotate in such bearings and to engage a locking-pin, substantially as described.
20. In a car-coupler, in combination, a pressed-metal draw-head made in two parts, as described, having its rear end re-enforced with a perforated **U**-strap adapted for the insertion of a tail-bolt, a knuckle rotating in 15 trunnion-bearings of unbroken circumference formed in each part of the head and adapted to engage a locking-pin, and a pin passing through the axis of the trunnions, securing the parts together, substantially as described.
21. In a car-coupler, in combination, a pressed-metal draw-head made in two parts, as described, having a bearing of unbroken circumference in each part, and a knuckle adapted to rotate in such bearings and to engage a locking-pin having two wings, one engaging the knuckle and the other a proper projection on the draw-head, substantially as described.
22. In a car-coupler, a pressed-metal draw-head made in two parts, as described, having a bearing of unbroken circumference in each part, and a knuckle, as described, to rotate in such bearings, in combination with a locking-pin having two wings, one adapted to be

engaged by the knuckle while closing and the other formed in steps arranged to fall behind and engage with a projection on the draw-head, substantially as described.

23. In a car-coupler, a pressed-metal draw-head such as described, having a bearing of unbroken circumference in each part, and a knuckle arranged to rotate in such bearings between suitable stops limiting its play, in combination with a locking-pin having two wings, one adapted to be engaged by the 45 knuckle while closing, and thus rotate the pin, and the other adapted to be engaged by the knuckle while opening after being lifted out of engagement with a stop on the draw-head, substantially as described.

24. In a car-coupler, a pressed-metal draw-head having bearings in each part and a knuckle arranged to rotate in each bearing having a wing **U**, provided with a flange **U'**, adapted to strike the side of the head to limit the play in one direction, a flange **U''**, engaging the locking-pin, and a stop **k**, limiting its play in the other direction, in combination with a rotating locking-pin having a wing provided with steps successively engaging a 55 projection on the draw-head by the rotation of the pin, substantially as described.

In witness whereof I have hereunto set my hand in the presence of two witnesses.

DAVID L. BARNES.
